(57) **CLAIM**

The ornamental design for a backpack clip, as shown and described.

DESCRIPTION

FIG. 1 is a front perspective view of a backpack clip showing our new design;

FIG. 2 is a rear view in perspective thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof; and,

FIG. 9 is a front view of the backpack clip shown in an environment which it is used.

The broken line illustration of environmental structure in FIG. 9 is not part of the claimed design.

1 Claim, 5 Drawing Sheets
